Des. 229,766
Patented Jan. 1, 1974

229,766

COMBINED TABLE AND AQUARIUM OR SIMILAR ARTICLE

Lynn H. Kephart, 2109 Skylark St.,
Arlington, Tex. 76010

Filed Feb. 22, 1972, Ser. No. 228,461

Term of patent 14 years

Int. Cl. D30—02

U.S. Cl. D30—11

Fig. 1.

Fig. 2.

Fig. 3.

Fig. 4.

Fig. 5.

FIG. 1 is a perspective view of a combined table and aquarium or similar article, showing my new design;

FIG. 2 is a cross-sectional view taken on line 2—2 in FIG. 1;

FIG. 3 is a side elevational view;

FIG. 4 is a top plan view;

FIG. 5 is a bottom plan view thereof.

I claim:

The ornamental design for a combined table and aquarium or similar article, as shown.
